UNITED STATES PATENT OFFICE.

FRANCIS A. FREETH, OF GREAT CROSBY, AND HERBERT E. COCKSEEDGE, OF LONDON,
ENGLAND.

SEPARATION AND RECOVERY OF POTASSIUM SALTS FROM COMMERCIAL NITRATE OF SODA CONTAINING SUCH SALTS.

1,300,947.

Specification of Letters Patent. Patented Apr. 15, 1919.

No Drawing.

Application filed February 12, 1917. Serial No. 148,292.

To all whom it may concern:

Be it known that we, FRANCIS ARTHUR FREETH and HERBERT EDWIN COCKSEEDGE, subjects of the King of Great Britain, residing at Great Crosby, in the county of Lancaster, England, and London, in the county of Middlesex, England, respectively, have invented certain new and useful Improvements in the Separation and Recovery of Potassium Salts from Commercial Nitrate of Soda Containing Such Salts, of which the following is a specification.

We have discovered a process for separating and recovering in a marketable form the potassium nitrate which frequently occurs in commercial nitrate of soda, thereby increasing the value of the sodium nitrate from which it has been extracted, inasmuch as the purified sodium salt will yield more nitric acid for a given weight of sulphuric acid employed than was the case with the crude niter from which the sodium nitrate has been obtained.

The process is based upon the fact that the proportion of potassium to sodium present in an aqueous solution saturated with respect to both potassium and sodium nitrates is considerably greater at higher temperatures (for example temperatures in the neighborhood of 100° C.) than at lower temperatures (for example at temperatures in the neighborhood of 20° C.).

The process consists essentially in digesting the crude nitrate of soda from which the potassium salts are to be extracted with water (or with wash waters from subsequent operations), the quantity of solvent liquor employed being such as will suffice to dissolve the whole of the potassium salts present in the crude nitrate of soda, and at the same time yield a solution saturated or nearly saturated with respect to potassium salts at the temperature at which the digestion was completed.

The solution thus obtained is of course also saturated with respect to sodium nitrate at that temperature, but as only sufficient solvent liquor is employed to dissolve the potassium salts, the bulk of the sodium nitrate remains undissolved.

The solution is separated from the undissolved portion at or about the same tem-

perature as that at which the digestion was completed.

This solution, if saturated with respect to potassium salts, or if not completely saturated, after concentration to saturation as subsequently described, is then diluted with sufficient water to keep the sodium nitrate in solution at the temperature to which the diluted solution is subsequently cooled. The solution is then cooled to that temperature, when potassium nitrate crystallizes out and is separated from the solution and washed to remove adherent mother liquor, being thus recovered in a pure or practically pure form.

The process is fully described as follows:

The solubility of potassium nitrate in water and in an aqueous solution of sodium nitrate decreases as the temperature decreases, and the maximum temperature at which the digestion of the crude nitrate of soda is conducted depends upon practical considerations which are governed by the percentage of potassium salts in the crude nitrate of soda in the direction that, in order to obtain a sufficient bulk of solution saturated or nearly saturated with respect to potassium nitrate at the temperature of digestion to enable that solution to be separated from the undissolved sodium nitrate with reasonable facility, (that is, in order to avoid the production of a magma which is too thick and pasty) the digestion should be performed at a lower temperature when the percentage of potassium salts in the crude nitrate of soda is low than when that percentage is high.

The crude nitrate of soda containing potassium salts is digested with water or with wash liquors obtained in a subsequent operation, preferably previously heated to a temperature not exceeding 80 to 100° C., or to such lower temperature as may be necessary to enable the digestion to be completed at a temperature not exceeding that which is best adapted to give the required bulk of solution saturated or nearly saturated with potassium salts at that temperature and which, as previously explained, depends upon the percentage of potassium nitrate contained in the crude nitrate of soda treated.

We may however raise the mixture of nitrate of soda and solvent liquor to the desired temperature by heating after admixture instead of or in addition to heating the 5 solvent liquor before admixture.

Instead of using water for the digestion, we may employ the wash liquors which result from washing with water the sodium nitrate which remains undissolved when the 10 digestion is completed, or the wash liquors which result from washing with water the sodium nitrate resulting from the subsequent concentration of the solution obtained by digesting the crude nitrate of soda, if 15 and when such subsequent concentration is performed; these wash liquors may be used either separately or together.

The quantity of water or of wash liquor employed for digestion is that which is sufficient or only a little more than sufficient 20 to dissolve the potassium salts in the crude nitrate of soda at the temperature at which the digestion is completed.

After digestion the solution is separated 25 from the solid by any well known means at as nearly as practicable the same temperature as that at which the digestion was finished. A solution is thus obtained as nearly saturated with potassium nitrate as is 30 practicable and also saturated with sodium nitrate.

If the solution thus obtained is not saturated with respect to potassium nitrate at the desired temperature, it is concentrated until 35 it is saturated with respect to potassium nitrate at a high temperature (for example at 100° C.), and the sodium nitrate precipitated during the concentration is separated from the solution at, or approximately at that 40 temperature.

If however the digestion process has been carried out at a sufficiently high temperature, subsequent concentration is not required and the separation of sodium nitrate 45 which occurs when this operation is performed is avoided.

The precipitated sodium nitrate may be rendered pure or practically pure by washing it with water or with a solution of sodium 50 nitrate, and the same treatment may be applied to the undissolved sodium nitrate separated from the magma after the process of digestion previously described.

The liquor resulting from the washing of 55 either or both of these crops of sodium nitrate with water may be subsequently employed for the digestion of the commercial nitrate of soda.

To the hot solution thus obtained, which 60 is saturated with respect to potassium nitrate and sodium nitrate at a high temperature, and from which any precipitated sodium nitrate has been removed, water is added in such quantity that the ratio of water to 65 sodium nitrate in the resulting solution is

the same or nearly the same as that which obtains in a solution saturated with respect to potassium and sodium nitrates at the temperature to which the solution is to be subsequently cooled.

The resulting solution is then cooled to that temperature or approximately to that temperature when potassium nitrate crystallizes out, which, after removal from the mother liquor and washing with water or with a solution of potassium nitrate, is pure or practically pure.

Inasmuch as the mother liquor from this operation is saturated or nearly saturated with respect to both potassium and sodium nitrates at the temperatures to which it was cooled, it may be concentrated until it is saturated or nearly saturated with respect to potassium nitrate at the temperature of concentration, the precipitated sodium nitrate removed from the solution at that temperature, water subsequently added to the solution, and the solution thus diluted cooled for separation of potassium nitrate as described above, and this cycle of operation 90 repeated indefinitely.

The wash liquor resulting from the washing of the sodium nitrate which remains undissolved after the digestion of the commercial nitrate of soda, and/or the wash liquor resulting from the washing of sodium nitrate separated out during the operation of concentration may be if preferred, again concentrated until it is saturated with potassium nitrate, the sodium nitrate precipitated during concentration removed from the solution, water added to the hot solution remaining until the ratio of water to sodium nitrate in the resulting solution is the same or nearly the same as that which obtains in a solution saturated with respect to potassium and sodium nitrates at the temperature to which the solution is to be subsequently cooled, the solution then cooled to that temperature, and the potassium nitrate which 100 crystallizes out from the solution removed and washed.

The wash liquor which results from the washing of the potassium nitrate may be concentrated until the ratio of sodium nitrate to water in the solution is the same as obtained in a solution saturated with respect to both sodium and potassium nitrates at the temperature to which the solution is to be subsequently cooled and the concentrated solution cooled to this temperature, when potassium nitrate crystallizes out, which after washing with water or with a solution of potassium nitrate is pure or practically pure.

We declare that what we claim is:

1. The process of separating potassium nitrate from commercial nitrate of soda which comprises extracting the potassium nitrate at an elevated temperature in the 130

form of an aqueous solution, separating the solution from the undissolved sodium nitrate, adjusting the composition of said solution by dilution so that on cooling to a given lower temperature it will deposit a considerable amount of potassium nitrate without depositing sodium nitrate, cooling the solution to said lower temperature, and separating the potassium nitrate crystallizing therefrom.

2. The process of separating potassium nitrate from commercial nitrate of soda which comprises extracting the potassium nitrate at an elevated temperature by digestion with a relatively small quantity of water, separating the solution from the undissolved sodium nitrate, adjusting the composition of said solution by dilution so that on cooling to a given lower temperature it will deposit a considerable amount of potassium nitrate without depositing sodium nitrate, cooling the solution to said lower temperature, and separating the potassium nitrate crystallizing therefrom.

3. The process of separating potassium nitrate from commercial nitrate of soda which comprises extracting the potassium nitrate at an elevated temperature by digestion with a wash liquor obtained in the process, separating the solution from the undissolved sodium nitrate, adjusting the composition of said solution by dilution so that on cooling to a given lower temperature it will deposit a considerable amount of potassium nitrate without depositing sodium nitrate, cooling the solution to said lower temperature, and separating the potassium nitrate crystallizing therefrom.

4. The process of separating potassium nitrate from commercial nitrate of soda which comprises extracting the potassium nitrate at an elevated temperature by digestion with an aqueous liquid in amount sufficient to yield a solution substantially saturated with potassium nitrate at the temperature of digestion, separating the solution from the undissolved sodium nitrate, adjusting the composition of said solution by dilution so that on cooling to a given lower temperature it will deposit a considerable amount of potassium nitrate without depositing sodium nitrate, cooling the solution to said lower temperature, and separating the potassium nitrate crystallizing therefrom.

5. The process of separating potassium nitrate from commercial nitrate of soda which comprises extracting the potassium nitrate at an elevated temperature in the form of an aqueous solution, separating the solution from the undissolved sodium nitrate, adjusting the composition of said solution so that on cooling to a given lower temperature it will deposit a considerable amount of potassium nitrate without depositing sodium nitrate, said adjustment being performed by

adding to the solution so much water that the solution will be saturated with sodium nitrate at the given lower temperature, cooling the solution to said lower temperature, and separating the potassium nitrate crystallizing therefrom.

6. The process of separating potassium nitrate from commercial nitrate of soda which comprises extracting the potassium nitrate at an elevated temperature in the form of an aqueous solution, separating the solution from the undissolved sodium nitrate, adjusting the composition of said solution so that on cooling to a given lower temperature it will deposit a considerable amount of potassium nitrate without depositing sodium nitrate, said adjustment being performed by concentrating the solution till it is saturated with potassium nitrate, removing the sodium nitrate which crystallizes out and adding enough water to keep the solution saturated with sodium nitrate at the given lower temperature, cooling the solution to said lower temperature, and separating the potassium nitrate crystallizing therefrom.

7. In a process for separating potassium nitrate from sodium nitrate, the step which consists in taking a solution which is nearly saturated with both salts at a low temperature, concentrating it till it is nearly saturated with potassium nitrate at a higher temperature, removing the precipitated sodium nitrate, adding water till the solution is not more than saturated with sodium nitrate at a given lower temperature, cooling to said lower temperature and removing the precipitated potassium nitrate.

8. The process of separating potassium nitrate from commercial nitrate of soda which comprises extracting the potassium nitrate at about 80° to 100° C. in the form of an aqueous solution, separating the solution from the undissolved sodium nitrate, adjusting the composition of said solution by dilution so that on cooling at about atmospheric temperature it will deposit a considerable amount of potassium nitrate without depositing sodium nitrate, cooling the solution to said lower temperature, and separating the potassium nitrate crystallizing therefrom.

9. The process of separating potassium nitrate from commercial nitrate of soda which comprises extracting the potassium nitrate at an elevated temperature in the form of an aqueous solution, separating the solution from the undissolved sodium nitrate, adjusting the composition of said solution by dilution so that on cooling to a given lower temperature it will deposit a considerable amount of potassium nitrate without depositing sodium nitrate, cooling the solution to said lower temperature, and separating the potassium nitrate crystallizing therefrom, the elevated temperature and the

volume of liquid for digestion being so chosen as to avoid the production of a too pasty magma on digestion by obtaining a sufficient volume of solution to enable said 5 solution to be separated from the undissolved sodium nitrate with reasonable facility.

10. The process of separating potassium nitrate from mixtures of sodium nitrate and potassium nitrate which comprises extracting the potassium nitrate at an elevated temperature in the form of an aqueous solution, separating the solution from the undissolved sodium nitrate, adjusting the composition 15 of said solution by dilution so that on cool-

ing to a given lower temperature it will deposit a considerable amount of potassium nitrate without depositing sodium nitrate, cooling the solution to said lower temperature, and separating the potassium nitrate 20 crystallizing therefrom.

In witness whereof, we have hereunto signed our names this 27 day of January 1917, in the presence of two subscribing witnesses.
